DEVICE ATTACHMENT

Martin M. Clayton, Baden, Pa., assignor to National Electric Products Corporation, a corporation of Delaware

Application December 3, 1937, Serial No. 177,872

3 Claims. (Cl. 248—65)

This invention relates to a mounting attachment for electrical raceways, channels, receptacles, and other electrical housings and devices. It has particularly great utility in the installation of that type of elongate, multi-receptacle device known as "multiple-outlet duct" or "plug-in strip."

When multiple outlet duct is installed at or in some sort of wall molding, such as a baseboard or chair rail, its location with respect to the underlying wall structure is fixed. If then the underlying wall structure be impenetrable to screws or nails, or if it be impenetrable in the regions of the duct prepared for them, difficulty is experienced in attaching the duct to the underlying wall structure. The use of screws or nails passed through the base wall of the duct channel, or through the base wall and cover presents some difficulty in manipulation, or increases the complexity of the duct structure. In the latter case, there is some objection to the appearance of screw heads overlying the duct cover. The same problems exist in varying degree with respect to the mounting of raceways, outlets, receptacles and the like in the walls of buildings.

With these problems in mind I have provided a mounting attachment for electrical housings and devices which permits mounted attachment of such structures without the use of screws or nails, where mounting of such sort is expedient; and which provides selectivity in the positioning of the actual attaching means on the structure to be mounted whether or no screws or nails be employed.

In effecting my purpose I provide a basal wall of the electrical housing or device which is to be mounted with a plurality of spaced means for engaging cooperatively with an attaching clip in the form of a resilient mounting plate adapted to be selectively engaged to the spaced engaging means on the basal wall of the electrical structure; the clip-engaging means on the basal wall of the electrical structure and the attaching clip being so related to the dimensions of the basal wall that the clip extends beyond one or more edges of the wall. Specifically, I so form the resilient mounting plate constituting the attachment clip as peculiarly to adapt it to the resilient mounting of a structure, to which it is engaged, to a wall molding, such as a baseboard or chair rail, and to provide for its firm engagement to the basal wall of the structure in its selected position thereon.

In the accompanying drawing Fig. I is a view showing my mounting attachment applied to a

channel of the sort suitable for use as an element of a multiple outlet duct housing, the view being taken in front elevation, and illustrating the selectively positioned engagement of the resilient mounting plates of the assembly to the basal wall of the electrical housing.

Fig. II is a view taken in rear elevation, showing the attachment of one resilient mounting plate to the basal wall of the electrical housing.

Fig. III is a longitudinal sectional view through the basal wall of the electrical housing in a region at which a mounting plate is attached to it, the view being taken on the section line III—III of Fig. I.

Fig. IV is a view taken cross sectionally of a baseboard standing against a wall surface; the view showing in cross-section a housing channel mounted to the baseboard and wall surface, without the use of screws or nails, by means of the mounting attachment of my invention and showing cross-sectionally, in broken lines, the channel and a mounting plate held against the wall surface in preparation for mounted attachment.

Fig. V is a cross sectional view through a wall structure and an electrical channel element mounted thereon by means of my mounting attachment, the direct attachment to the wall being by means of screws.

Referring to Fig. I of the drawing, the channel element 1 therein shown is of a shape appropriate for use of an element of a multiple outlet duct housing. The mounting plate 2 is resilient and lies against the outer surface of the basal wall 3 of the channel, with its portions 4 and 5 extended beyond the longitudinal edges 35 of the wall. A hole 6, for the passage of a penetrating member such as a screw or nail, is formed in each of the extended portions 4 and 5 of the mounting plate. One portion of the mounting plate, extended beyond a longitudinal edge 40 of the basal wall 3, is as a whole deflected away from the plane of the wall, but has a tip 5a reversely deflected to stand approximately parallel to the plane of the wall.

The wall 3 of the channel is adapted in several spaced regions to engagement with a mounting plate of the sort described. The engaging means shown are simple, and are adapted to make a snap engagement with the resilient mounting plate. They each are formed by means 50 of two adjacent, parallel slits 7 and 8, at one of which the material of the wall 3 is deflected inwardly of the channel to provide an opening 7a, and at the other of which the material of the

wall is deflected outwardly to form a shoulder 8a.

In its central region mounting plate 2 is cut, and the material bounded by the cut is deflected, to form a tongue 9 offset from that face of the mounting plate which lies in assembly against the surface of the basal wall 3. In making assembly engagement of a mounting plate at a region of the wall 3 arranged for its reception, the tongue 9 of the mounting plate is inserted in the opening 7a and the mounting plate is moved horizontally until the base of the tongue contacts the edge of the slit 7. If the mounting plate is slightly forced in this position, its trailing edge snaps into abutment with the shoulder 8a. To remove the mounting plate from engagement with the wall, this edge is lifted sufficiently to ride over the shoulder 8a, and the tongue 9 is withdrawn from opening 7a by horizontal movement of the mount-plate.

If now we consider that channel 1 may be a number of feet in length, it is a simple matter "on-the-job" to apply clips to it at several longitudinally spaced points, either in conformity to those portions of a wall which are adapted to receive nails or screws, or merely to balance along the channel the points at which it is to be attached.

Fig. V of the drawing shows the channel 1 mounted to the surface of a wall 10 by means of screws 11 passed through the holes 6 in the portions 4 and 5 of the mounting plate which are extended beyond the longitudinal edges of the basal wall 3 of the channel. In mounting the channel, or other housing structure, in this manner, the deflected portion 5, which extends beyond the edge of basal wall 3, may be forced into approximate alignment with the remainder of the mounting plate by forcing it against the wall 10.

In Fig. IV of the drawing, a side wall of the channel 1 lies upon the upper edge of a baseboard 12, with the basal wall 3 of the channel against an underlying wall 13. In this sort of mounting the attachment of the channel is by the insertion of its extended and deflected portion 5 between the opposed surfaces of the baseboard 12 and wall 13. As inserted between two such elements, the deflected portion of the mounting plate is placed under compression, and thus locks the channel in its mounted position. Desirably, as shown, this deflected portion of the mounting plate lies at a relatively great angle to the plane of the basal wall to which the mounting plate is attached, and to the rest of the mounting plate, in order that the advantage of this compression may not be lost when there is an appreciable space between the opposed surfaces of the wall and the baseboard. Because of the relatively great deflection of one extended portion of the mounting plate, the reverse deflection at the tip 5a is of advantage in inserting the deflected portion between two surfaces which lie close to each other.

It will be noted that in the showing of Fig. IV the mounting plate 2 has but one portion extended beyond an edge of the basal wall of the channel. The other extended portion 4 has been broken away in order to improve the appearance of the duct of which the channel 1 forms part, since the duct in this showing forms what is in effect the trim of the baseboard on which it lies.

This extended portion 4 may readily be broken away at the score line 14 (Fig. II), which matches one longitudinal edge of the wall 3. If, however, the baseboard structure comprises a trim adapted to surmount the duct, this projecting portion 4 is preferably allowed to remain part of the mounting plate; because it is in such circumstance concealed, and as it lies between the trim and the wall surface provides additionally against dislodgment of the duct.

While the mounting attachment of my invention is shown and described as forming part of the channel of a multiple outlet duct, it is to be understood that it is equally applicable to raceways, outlet boxes, receptacles, and other electrical housings and structures having a basal wall to which one or more of the mounting plates may be engaged. In such varied structures the mounting attachment has utility, and provides advantage measurable by the difficulty normally encountered in mounting each particular structure in accordance with previous common practice.

I claim as my invention:

1. In electrical raceways, housings, and like electrical devices the herein described mounting attachment comprising in combination a basal wall forming part of the element to be mounted, said wall having an opening therein and a projection on the said wall spaced from said opening, with a resilient mounting plate at a face of the said wall and having a region thereof extended beyond an edge of the wall and deflected away from the plane of the wall, the said resilient mounting plate having a tongue adapted to enter the said wall opening to engage the mounting plate to the wall and arranged to lie in assembly in edge abutment with the said wall projection.

2. In electrical raceways, housings, and like electrical devices the herein described mounting attachment comprising in combination a basal wall forming part of the element to be mounted said wall having therein a pair of spaced slots and the body of the wall being outwardly deformed at one of said slots to form a shoulder, with a mounting plate lying against said wall and having a region extended beyond an edge of the wall, said mounting plate having a tongue adapted to enter one of said slots to interlock with the wall and having a snap engagement between that slot and the shoulder formed at the other of said slots.

3. In electrical raceways, housings, and like electrical devices, the herein described mounting attachment comprising in combination a basal wall forming part of the housing structure to be mounted, said wall having an opening therein, with a resilient removable mounting plate lying flat against a face of the said wall and arranged to project beyond an edge of the wall, said resilient mounting plate having a member adapted to engage in said wall opening, and additional plate-engaging means in the said wall so positioned with respect to the said wall opening that engagement of the resilient mounting plate simultaneously with both the wall opening and the said additional plate-engaging means is effected by forcing the mounting plate by its resiliency into its fully engaged position on the said basal wall.

MARTIN M. CLAYTON.
